[57] CLAIM

The ornamental design for a wrench for a pool vacuum cover, as shown and described.

DESCRIPTION

FIG. 1 is a perspective view of a wrench for a pool vacuum cover showing my new design, with a person and a vacuum lid cover in broken lines for illustrative purposes only and forming no part of the claimed design;

FIG. 2, is a front elevational view thereof;

FIG. 3, is a rear elevational view thereof;

FIG. 4, is a left side elevational view thereof;

FIG. 5, is a right side elevational view thereof;

FIG. 6, is a top plan view thereof; and,

FIG. 7, is a bottom plan view thereof.
